UNITED STATES PATENT OFFICE.

PHILIP MUELLER AND ANTON C. SCHUERMANN, OF DECATUR, ILLINOIS, ASSIGNEES
TO ADOLPH MUELLER, TRUSTEE, OF DECATUR, ILLINOIS.

RECEPTACLE-ACTUATED COCK.

Application filed October 28, 1919. Serial No. 334,167.

To all whom it may concern:

Be it known that we, PHILIP MUELLER and ANTON C. SCHUERMANN, citizens of the United States, and residing at Decatur, in the county of Macon and State of Illinois, have invented new and useful Improvements in Receptacle-Actuated Cocks, of which the following is a specification.

The present invention relates to cocks, and, particularly, to a receptacle actuated cock, in which, on presentation of a drinking cup or other container to the nozzle, the valve of the cock will be actuated and fluid delivered, and upon withdrawal of the vessel, the valve will automatically close to cut off the flow.

The arrangement is such, furthermore, that sanitary use of the cock or faucet is compelled; and, additionally, provision is made for protecting fragile or breakable containers, such as glasses and the like, from being broken by careless users of the cock.

It has as a further object, to provide valve regulating means by which proper seating of the valve may be conveniently and accurately secured in its initial assembling, and, thereafter, adjustments necessitated by wear of the valve readily taken care of.

In order that the invention may be clear to those skilled in the art, we have shown in the accompanying drawings, embodiments of our invention, and in said drawings:

Figure 1 is a view, in side elevation, of a cock having our improvements applied thereto.

Figure 2 is a view in rear elevation, of the cock shown in Figure 1.

Figure 3 is a detail view, in elevation, of the cock nozzle, showing the valve operating sleeve.

Figure 4 is a view, in perspective, of the sleeve and valve-operating link.

Figure 5 is a view in vertical section of the cock nozzle and the valve mechanism.

Figure 6 is a bottom plan view of the nozzle shown in Figure 5.

Figures 7 and 8 are, respectively, vertical sectional and bottom plan views of a different species of valve.

Figures 9 and 10 are, respectively, vertical sectional and bottom plan views of another species of valve.

Figure 11 is a vertical sectional view of still another species of valve.

Figures 12 and 13 are detail views in section and perspective, respectively, of valve-adjusters.

Figures 14 and 15 are, respectively, vertical sectional and bottom plan views of still further species of valve.

Figure 16 is a view in side elevation, of a cock having valve-actuating means of the same general form as the form shown in Figures 1 and 2, but differing therefrom as to some of the details.

Figure 17 is a sectional view to illustrate the buffer construction.

Figure 18 is a view in rear elevation of the buffer, the fastening screw being shown in cross section.

In the drawings, referring to them by numbers, and, first, to Figure 1, 10 indicates a cock-body of any suitable or desired form, provided with means for attachment to a service pipe.

The discharge end or nozzle of the cock 10 is provided with a sliding sleeve 11, (see Figures 3 and 5), which has a limited play on the end of the cock. The sleeve 11 is provided at its lower end with a cross-bar or strut 14, in which is mounted the lower end of a valve actuating rod 16, preferably threaded for purposes of valve-adjustment relative to the sleeve. The upper end of said rod 16 engages the downwardly projecting stem 16^a threaded upwardly into the valve 17 as shown, although it may be secured in any suitable manner.

The said valve 17 seats on a valve seat 18 formed in the cock 10, and has means, as the spring 19 surrounding the valve-stem 20, to hold the valve normally to its seat, said spring bearing at its upper end against an abutment, (not shown).

The rod 16 and the stem 16^a are preferably just out of contact with each other, as shown, when the parts are in a state of rest with the valve closed, so that there will be no danger of the valve 17 failing to seat properly and give a tight fit, but the separation of rod 16 and stem 16^a is so slight that sufficient lost motion does not occur to interfere with the proper opening of the valve when it is operated by the mechanism now to be discussed. In order that adjustment to compensate for

wear of the valve may be secured, the rod 16 is preferably split at its lower end, as shown, for the reception of a screw-driver or other suitable tool, and such split end has 5 also a binding effect tending to hold the rod 16 in adjustable position.

The sleeve 11 is provided with outstanding pins or lugs 21, which are engaged by links 22 (two being shown), preferably hooked as 10 at 23 for ready assembling. Said links 22 are slotted at 24 to engage pivot pins 25 on the cock-body, and have the outstanding portions 26 at their upper ends.

Pivoted on the pins 25 are the forks of a 15 lever 27, which is preferably formed as shown, of two plates riveted together, altho it may be formed in any suitable or desired fashion. Each fork of the lever 27 is provided with a cam surface 28 which engages 20 the portions 26 on the links 22. The lever 27 is preferably provided with a stop 29, which, as shown in Figure 1, rests against the sleeve 11 or any other convenient part of the 25 cock so as to maintain the lever 27 in a normally vertical or substantially vertical position. At its lower end the lever 27 is forked to provide two receptacle engaging forks 30, provided preferably with buffers 31 of soft material, against which the glass (indicated 30 in dotted lines in Figure 1) will bear.

By the arrangement of operating mechanism just described, the sleeve 11 with its valve-actuating rod, is given a straight vertical lift, in parallelism with the longitudinal axis of the cock body, and no side strain is put upon the sleeve tending to cause a binding action of the sleeve on the cock. The buffers 31 are preferably formed as shown, and comprise a nut 31^a which is embedded in the cover 31^b of molded or other suitable material which completely envelops the nut, except for the small annular area 31^c surrounding the threaded opening in the nut and which receives the screw 31^d by 40 which the buffer is attached to the arm 30 of the lever. With this construction a very effective buffer is provided, for the nut 31^a is completely enveloped in the cushioning material, which, it will be observed, lies between the nut and the face of the arm, and, furthermore, encloses the end of the screw, so that a complete cushioning of the metal 45 parts and the receptacle is secured.

In operation, the glass will be pushed inwardly against the buffers 31 and the lever 27 will be swung from the full-line position shown in Figure 1, to the dotted line position illustrated in that Figure. The swinging of the lever 27 on its pivot will 50 cause a camming action of the cam 28 on the portion 26, rasing the links 22 in a straight line, elevating the sleeve 11, opening the valve 17, and permitting flow thru the nozzle. The glass will be in the 55 dotted line position shown in Figure 1, im-

mediately beneath the nozzle. When the glass is filled and withdrawn from the forks 30, the valve 17, under action of the spring and the flow of the liquid, will close, forcing the sleeve downwardly, together 70 with the links 22, and the lever 27 will fall to its full-line normal position.

We preferably provide the lever 27 with one or more arms 32, located between the forks 30 and the end of the nozzle, and 75 these arms have a two-fold function. They are so positioned that they engage the top of the glass as it is brought into contact with the lever, as indicated in dotted lines in Figure 1, thus preventing the glass striking 80 the nozzle which might result in breakage. In addition to this function, they have still a further and very important function of preventing careless users of the drinking receptacles from bringing the receptacle up so 85 as to immerse the nozzle therein, which in case of unclean receptacles might contaminate the nozzle.

In the form of invention shown in Figures 9 and 10, the disposition of the valve 90 and the sleeve are generally as in the forms heretofore described, but in lieu of the adjustable screw, shown in the other form, we provide the nozzle with an adjustable nipple 38 having the strut or cross bar 39 at its top 95 bearing against the valve-operating rod 40. The nipple 38 is preferably screw-threaded into the sleeve, as shown, and provided with spanner notches 41, by means of which it may be adjusted, and preferably has, as 100 shown in Figure 9, drainage openings 42 to clear the nozzle of water.

In the form shown in Figures 11 and 13, the arrangement is similar to that disclosed in Figures 9 and 10, except that the nipple 105 42^a is provided with slots 43, by means of which it may be adjusted thru the medium of an ordinary screw driver, and such splitting of the sleeve gives a spring-gripping action which tends to bind the nipple in adjusted 110 position, and drainage openings 44 are provided so as to eliminate the possibility of water being caught and held within the nozzle or sleeve, and, furthermore, to give sufficient area to eliminate back pressure and 115 leakage between the sliding sleeve and nozzle.

In the form shown in Figures 11, 12 and 13, the strut or cross-bar 42^b is preferably provided with a nick or depression 42^c on its 120 underside to receive a screw-driver, so as to effect the necessary adjustments to compensate for valve wear.

In Figures 14 and 15, the nipple 45 is provided, by means of which adjustment of the 125 valve is effected, this nipple having a cross-bar 46 to bear on the valve rod 47, and being provided with spanner openings 48, by means of which adjustment of the nipple and valve is secured. In the form shown in these fig- 130

ures, drainage and increased area of discharge is effected by means of the openings 49, formed in the sleeve, the nipple 45 being threaded into the inner wall 50 of that sleeve, as shown in Figure 14, and flow area is further increased by the openings 50^a formed in the upper edge of the nipple.

In Figure 16 we have shown a slightly different form of sleeve-actuating mechanism. In the construction shown in Figure 16, the body of the cock, the sleeve, and the valve mechanism, may be of any of the types shown. The lever 51, has the forked end 52, but in this form we have dispensed with the links and their operating cams, as disclosed in the above figures, the levers 51 being pivoted directly to the cock-body as at 53, having the stop 54 as in the other type, and the glass engaging forks 55 at the lower end of the lever. The lever 51 is provided, however, with cam arms 56, projecting forwardly of the lever, and straddling the sliding sleeve at the end of the nozzle, the cam arms 56 engaging the cam rolls 57 carried by the sleeve 58.

In operation, when the glass is forced against the forks 55, the lever 51 will swing on its pivots 53, rocking the lever 51 back to substantially the same position as the lever shown in Figure 1, and therein illustrated in dotted lines. The cam arms 56 will ride beneath the cam rolls 57, lifting them together with the sleeve 58 with a straight vertical lift and opening the valve. On withdrawal of the receptacle, the sleeve 58 will, by spring and fluid pressure, be forced down and the valve brought to its seat, and the cam rolls 57 acting thru the cam arms 56 will return the lever to the normal, full line position shown in Figure 16.

We have illustrated our improvements in connection with valves of conical form, and while we do not limit ourselves to any particular form of valve, we find the adjustable feature for regulating the valve of particular advantage in connection with coned valves. The valves when they leave the factory are, of course, perfectly fitted, but if replacements are necessary, it might happen that the coned valve would not be accurately fitted to its seat. In event of that condition, the cone would perhaps seat in the upper part of the valve seat, and there would be too much lost motion between the valve stem and the actuating rod on the sleeve; or the cone might project through the seat opening too far, and, resting on the valve-actuating rod or abutment, prevent proper closing of the valve on its seat. By the adjustable members shown, such discrepancies can be taken care of and proper valve operation and seating insured.

It will be understood that such variations as are within the knowledge of mechanical skill may be made without departing from

the spirit of our invention, and we do not, therefore, limit ourselves to the illustrated disclosure herein, except in so far as we are limited by the prior art and the terms of the appended claims.

We claim the following:

1. A cock, having in combination, a normally-closed valve, a vertically movable member carried by the cock-body, means for moving said member, and a hollow valve-actuating nipple having a screw-thread connection with said member.

2. A cock, having in combination, a normally-closed valve, a vertically movable member carried by the cock-body, means for moving said member, and a hollow valve-actuating nipple having a screw-thread connection with said member, said nipple having a drainage opening in its wall.

3. A cock, having in combination, a normally-closed valve, a vertically movable member carried by the cock-body, means for moving said member, and a hollow valve-actuating nipple having a stem-engaging strut screw-threaded in said member.

4. A cock, having in combination, a normally-closed valve, a vertically movable member carried by the cock-body, means for moving said member, and a hollow valve-actuating nipple having a screw-thread connection with said member, and provided with a stem-engaging strut, said strut being provided with a tool receiving recess on its under side.

5. Valve actuating means for cocks comprising a member slidably relative to the valve and an exteriorly threaded nipple carried by said slidably member having a strut at its upper end to engage and open the valve.

6. Valve actuating means for cocks comprising a member slidably relative to the valve and an exteriorly threaded hollow nipple carried by said slidably member having a strut at its upper end, to engage and open the valve and being slotted at its lower end to permit engagement of a tool therewith.

7. Valve-actuating means for cocks comprising an exteriorly threaded hollow nipple having a stem-engaging strut at its upper end provided with a tool receiving nick, said nipple being slotted at its lower end and provided with a drainage opening in its wall.

8. A cock having in combination, a normally-closed valve, a valve-actuating member carried by the cock-body, a swinging bracket pivoted on the cock-body, and vertically disposed links connecting said bracket and valve-actuating member to effect a straight lift of said member.

9. A cock, having in combination, a normally-closed valve, a valve-actuating sleeve vertically movable on the cock-body, a

bracket pivoted on the cock-body vertically disposed links connecting said bracket and valve-actuating member, and cam surfaces on said bracket to engage said links to effect 5 a right line movement of said links and member.

10. A cock having in combination, a normally-closed valve, a valve-actuating sleeve mounted on the cock-body, a bracket pivoted on the cock-body, links connecting said bracket and sleeve, and provided with cam receiving projections and cam surfaces on said bracket to engage said projections and move said links and sleeve vertically.

15. 11. A cock having in combination, a normally-closed valve, valve-actuating means mounted on the cock-body, a swinging bracket pivotally mounted on the cock-body and operatively connected with said valve-

20 actuating means, and a guard arm so disposed as to engage the top edge of a receptacle extending forwardly from said bracket below the nozzle of the cock.

12. A cock having in combination, a normally-closed valve, a valve-actuating sleeve 25 slidably mounted on the cock-body, a sleeve-actuating bracket pivoted on the cock-body and operatively connected with said sleeve, and receptacle guide arms projecting forwardly from said bracket and straddling 30 the lower end of said cock.

13. A cock having in combination, a normally-closed valve, a valve-operating sleeve slidably mounted on the cock-body, a sleeve-actuating bracket pivotally mounted on the 35 cock-body, a link having its lower end connected with said sleeve and its upper end in slotted engagement with the pivot of said bracket, and a cam surface on said bracket to engage said link and actuate said sleeve 40 and valve when the bracket is swung on the pivot.

In testimony whereof we have hereunto set our hands.

PHILIP MEULLER.

ANTON C. SCHUERMANN.
